UNITED STATES PATENT OFFICE.

GUSTAV HERMAN MAHN, OF CLINTONVILLE, WISCONSIN.

CISTERN.

1,085,217.

Specification of Letters Patent. Patented Jan. 27, 1914.

Application filed June 4, 1913. Serial No. 771,664.

To all whom it may concern:

Be it known that I, GUSTAV HERMAN MAHN, a citizen of the United States, residing at Clintonville, in the county of Waupaca and State of Wisconsin, have invented certain new and useful Improvements in Cisterns, of which the following is a specification.

This invention relates to cisterns used for storing rain-water from roofs of houses or other places, and its object is to provide a novel and improved device which automatically cuts off the flow to the cistern when the same is full, and directs the flow to a waste pipe.

It is also the object of the invention to provide a cut-off device which is simple in construction and efficient and reliable in operation, which can be readily installed and which will not prevent access to the cistern for the purpose of cleaning the same.

These objects are attained by means of a combination and arrangement of parts to be hereinafter described and claimed, reference being had to the accompanying drawing, in which—

Figure 1 is an elevation of the cut-off device, a fragment of the cistern being shown in section. Fig. 2 is a vertical section. Fig. 3 is a section on the line 3—3 of Fig. 1. Fig. 4 is a section on the line 4—4 of Fig. 1.

In the drawing, 5 denotes a cistern of ordinary construction, and 6 is a down pipe leading from the roof, and having branches 7 and 8 respectively. The branch 7 is arranged to discharge into the cistern, and the branch 8 is connected to a waste pipe which may lead to any desired place. At the junction of the pipes 6, 7 and 8 is a cut-off plate 9 which is carried by pivots 10, and so arranged that when tilted in one direction it closes the pipe 8 and leaves the pipe 7 open and in communication with the pipe 6, and when tilted in the opposite direction the pipe 7 is closed and the pipe 8 is placed in communication with the pipe 6.

To effect the tilting movement of the cut-off plate 9 automatically, a float operated mechanism is provided which will now be described. To the under side of the top 11 of the cistern 5 are secured two spaced cross-strips 12 carrying two parallel and spaced boards 13 set vertically, to each of which latter are secured depending guide strips 14.

These parts form a guide for the float and a support for a pulley to be presently described. Each board 13 carries two strips 14 which are spaced apart a sufficient distance to form a guideway, the strips of the respective boards being arranged so that the guideways are in alinement. Two floats are provided, the same being indicated at 15 and connected by cross bars 16. The floats are located on the outside of the respective pairs of strips 14, and the cross bars 16 pass loosely through the guideways formed by said strips and thus guide the floats. Between the boards 13 is located a grooved pulley 17 which is carried by a shaft 18 extending transversely between said boards and supported thereby. In the pipe 7 is mounted a guide pulley 19. To the top cross bar 16 is made fast a line 20 which passes upward over the pulley 17 and thence extends to the pulley 19, and after passing behind the same, is carried to the plate 9 and made fast to that end of the latter which works across the pipe 7. One of the pivots 10 passes through the wall of the pipe, and on the outside thereof carries a grooved sheave 21 to which is fastened one end of a line 22 carrying at its other end a weight 23, which latter tends to unwind the line and rotate the sheave in one direction. When the sheave is rotated in the opposite direction, the line is wound thereon. The weighted line is so arranged that it tends to normally rotate the sheave in a direction to place the cut-off plate 9 across the pipe 7 to shut off the same from the pipe 6.

When the cistern 5 is empty, the floats 15 are down, and through their connection with the cut-off plate 9 they have swung the latter to close the pipe 8 and to open the pipe 7, as shown in Fig. 2. When the cut-off plate is swung to this position, the line 22 was wound on the sheave 21. The weight of the floats is, of course, sufficient to overbalance the weight 23. Rain-water may now enter the cistern through the pipe 7, and when the water level reaches the floats, they are carried upward, whereupon the line 20 is slackened. The weight 23 then unwinds the line 22 and rotates the pulley 21 in a direction to swing the cut-off plate across the pipe 7 and away from the pipe 8. Thus, the flow to the cistern is cut off and directed to the waste pipe. When the water level in the cistern drops, the floats drop 110

and restore the parts to their normal position.

It will be noted that the floats do not extend down to the bottom of the cistern, but are located near the top thereof, thus leaving the cistern readily accessible for cleaning purposes, and as the float-guides are carried by the cistern top or cover 11, the latter, upon removal, takes with it the 10 guides and the floats. In the pipe 7, close to the pulley 19, are two wires 24 between which the line 20 passes, which prevents the line from slipping off said pulley. The 15 guide strips 14 carry pivoted pins 25 adapted to be placed beneath the upper cross bar 16 as shown by dotted lines in Fig. 2, for the purpose of locking or holding the floats 15 elevated when so desired. The guide strips opposite the ones to which the pins 20 are pivoted have abutments 26 engageable

by the free ends of the pins to hold the same in locking position.

I claim:

The combination with a cistern, of spaced members mounted on the under side of the 25 cistern top, guide strips depending from said members, a pulley mounted between the members, floats located on the outside of the guide strips, a cross bar connecting the floats and passing between the guide strips, 30 a cut-off device, and a line connected to the floats and passing over the aforesaid pulley to one end of the cut-off device and made fast thereto.

In testimony whereof I affix my signature 35 in presence of two witnesses.

GUSTAV HERMAN MAHN.
